(57) **CLAIM**

The ornamental design for drone aircraft, as shown and described.

DESCRIPTION

1. Drone (aircraft)

2. Drone (aircraft)

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

The second design corresponds to the “open position” version of the first design.
